UNITED STATES PATENT OFFICE.

WILLIAM H. FARNE, OF WILLIAMSON, WEST VIRGINIA.

ATTACHMENT FOR MINING MACHINES.

Application filed November 28, 1924. Serial No. 752,654.

To all whom it may concern:

Be it known that I, WILLIAM H. FARNE, a citizen of the United States, residing at Williamson, in the county of Mingo and 5 State of West Virginia, have invented certain new and useful Improvements in an Attachment for Mining Machines, of which the following is a specification.

This invention relates to a highly novel 10 means for use in connection with a coal mining machine wherein the latter is adapted to make a transverse cut in the coal, the purpose of the aforementioned means being to support the cutter means of the 15 mining machine in a horizontal position during the operation of the machine.

With the coal mining machines now in use of the type which employ an endless cutter chain whereby a transverse cut is 20 made in the coal, there is a tendency for the cutter means to tilt either upwardly or downwardly. In order to prevent such tilting action and to normally hold the cutter means in a horizontal position whereby 25 the machine may properly and efficiently operate, I have provided a simple and efficient means which is manually controlled.

A still further object of the invention is 30 to provide an attachment of the above mentioned character, which may be easily and readily secured in position on a coal mining machine, the device being simple in construction, inexpensive, strong and durable and furthermore adapted for the purposes 35 for which it is designated.

Other objects and advantages of this invention will become apparent during the course of the following description.

In the accompanying drawing forming a 40 part of this specification and in which like numerals designate like parts throughout the same:

Figure 1 is a top plan view of the attachment embodying my invention showing 45 the same applied.

Figure 2 is a side elevation with the holder in its uppermost position, and

Figure 3 is a fragmentary sectional view 50 taken approximately on line 33 of Figure 2 looking in the direction of the arrows showing the roller in its normal position.

In the drawing, wherein for the purpose of illustration is shown the preferred embodiment of my invention, the numeral 1 55 designates generally a coal mining machine of the type which employs the longitudinal-

ly extending cutter bar 2 and around which is adapted to travel the endless cutter chain 3 in the manner well known in the art. As the above elements form no important part 60 of the present invention, a further detailed description thereof is not thought necessary.

My improved attachment comprises a longitudinally extending shaft 4 which is supported in suitable bearings 5 at its respective ends between the cutter bar. The forward portion of the cutter bar is cut away as illustrated at 6 and the purpose thereof will be presently apparent. A pair of spaced supporting arms 7 and 8 respectively 70 are supported at their inner ends on the forward end of the shaft 4 and extend laterally into the cut out portion 6. A roller 9 is journaled at its end between the outer ends of the supporting arms 7 and 8 and normally the roller is disposed within the cut out portion 6. Secured to the rear end of the shaft 4 and extending laterally therefrom is a lever 10. The lever 10 is also adapted to be disposed in a cut out portion 75 11 provided in the rear end of the cutter bar 2 as clearly illustrated in the drawing.

A stationary nut 12 is secured to the forward end of the motor housing 13 and threaded vertically through the nut 12 is the feed screw 14. A swivel head 15 is associated with the lower end of the feed screw 14 and a link 16 affords a connection between the swivel head 15 and the outer end of the lever 10 as more clearly illustrated in Figure 3. An operating handle or lever 17 is associated with the upper end of the feed screw 14.

When the mining machine is in operation, the cutter means which travels in a horizontal plane has a tendency to tilt and often times as a result of the tilting action, serious injury to the cutting bits occur necessitating the replacing of the broken bits. Furthermore, the efficient mining of the coal is affected due to such tilting action. With my improved attachment, the cutting means will at all times be supported in proper position so that the same will maintain a transverse cut in a horizontal plane. Normally the roller 9 is disposed within the cut out portion 6 and should the forward end of the mining machine tilt upwardly, the handle 17 is turned in one direction causing the feed screw 14 to move vertically and upwardly 105 through the stationary nut 12 simultaneously causing the shaft 4 to be rotated through 110

the medium of the lever 10 so as to swing the roller 9 upwardly.

The upward swinging movement of the roller 9 will cause the same to come in contact with the ceiling of the cut made by the cutter means and will as a result cause the cutter means to maintain a horizontal cutting position.

Should the cutter means tilt in a downward direction, the handle 17 is rotated in the reverse direction causing the feed screw 14 to move downwardly and simultaneously rotating the shaft 4 in the reverse direction whereby the roller 9 carried by the outer end of the supporting arms or brackets 7 and 8 moves downwardly through the cut out portion 6 and engage the bottom of the cut made by the cutter chain 3. This will also return the cutter means to its normal horizontal cutting position whereby the same may efficiently operate in carrying out the mining of the coal.

The simplicity of my device enables the same to be readily and easily secured in position on a coal mining machine of the character above set forth and may be easily and efficiently operated whenever it becomes necessary.

While I have shown the preferred embodiment of my invention, it is to be understood that various changes in the size, shape and arrangement of parts may be resorted to without departing from the spirit of the invention and the scope of the appended claims.

Having thus described the invention, what I claim is:

1. In combination with a mining machine including the cutter means thereof, said cutter means being provided with a cut out portion, of means for maintaining the cutter means in a horizontal position during the operation of the machine comprising a shaft associated with the cutter means, a roller eccentrically carried by the forward end of the shaft and normally disposed in said cut out portion in the same plane with the cutter means, means associated with the opposite end of the shaft for actuating the same to cause the roller to swing in a vertical plane in either direction through the cut out portion, said means comprising a lever secured at one end to the rear end of said shaft, a vertically adjustable member, a connection between the lower end of the

vertically adjustable member and the outer end of the lever, and means for actuating said member, and also maintaining it in any desired position.

2. In combination with a mining machine including the cutter means thereof, said cutter means being provided with a cut out portion, of means for maintaining the cutter means in a horizontal position during the operation of the machine comprising a shaft supported on the cutter means, a roller eccentrically carried by the forward end of the shaft and normally disposed in said cut out portion in the same plane with the cutter means, means associated with the opposite end of the shaft for actuating the same to cause the roller to swing in a vertical plane in either direction through the cut out portion, said means comprising a lever secured at one end to the rear end of the shaft a vertically adjustable feed screw, a swivel head on the lower end thereof, a connection between the swivel head and the outer end of said lever, and a handle associated with the upper end of the feed screw for actuating the same.

3. In combination with a mining machine including the cutter means thereof, said cutter means being provided with a cut out portion, of means for maintaining the cutter means in a horizontal position during the operation of the machine comprising a shaft mounted on the cutter means, a pair of spaced arms secured on the forward end of said shaft and extending laterally therefrom into said cut out portion, a roller journaled in the outer ends of said arms, and normally disposed in the cut out portions in the same plane with the cutter means, means associated with the opposite end of the shaft for actuating the same to cause the arms and the roller to swing in a vertical plane in either direction through the cut out portion, said means comprising a lever secured at one end to the rear end of the shaft, a vertically adjustable feed screw, a swivel head on the lower end thereof, a connection between the swivel head and the outer end of said lever, and a handle associated with the upper end of the feed screw for actuating the same.

In testimony whereof I affix my signature.

WILLIAM H. FARNE.
